BILLBOARD

Lutrelle P. Wassmann, 211 5th, Wilmette, Ill.

Filed Oct. 20, 1961, Ser. No. 67,178

Term of patent 14 years

(Cl. D1—12)

FIG. 1

FIG. 1 is a front perspective view of a billboard showing my new design;

FIG. 2 is a front elevational view of the same, the rear being essentially plain; and

FIG. 3 is a top plan view of the same, the bottom being substantially the same.

I claim:

The ornamental design for a billboard, substantially as shown and described.
